UNITED STATES PATENT OFFICE.

HALLIE D. SWAIN, OF MERIDIAN, MISSISSIPPI.

CANT HOOK.

Application filed October 28, 1921. Serial No. 511,163.

To all whom it may concern:

Be it known that I, HALLIE D. SWAIN, a citizen of the United States of America, and resident of Meridian, in the county of

5 Lauderdale and State of Mississippi, have invented certain new and useful Improvements in Cant Hooks, of which the following is a specification.

This invention relates to cant hooks, and 10 it has for an object the provision of novel means whereby the cant hook may be manipulated to more effectually move logs and the like, and in which provision is made for bracing action of the hook during the 15 manipulation of the stock; and furthermore in the provision of novel means for insuring a firm anchorage of the nose of the stock as it engages the log to be moved.

It is a still further object of this invention 20 to provide a cant hook having a mounting to which the hook is pivotally connected and by which the oscillation of the hook is limited, in order that it may be held and caused to stand at a proper angle 25 with relation to the stock.

With the foregoing and other objects in view, the invention consists in the details 30 of construction, and in the arrangement and combination of parts to be hereinafter more fully set forth and claimed.

In describing the invention in detail, reference will be had to the accompanying drawings forming part of this application wherein like characters denote corresponding 35 parts in the several views, and in which—

Figure 1 illustrates a view in elevation of a cant hook embodying the invention;

40 Figure 2 illustrates a sectional view on the line 2—2 of Fig. 1 with parts omitted;

Figure 3 illustrates a perspective view of the hook clip;

Figure 4 illustrates a detailed view on the line 4—4 of Fig. 1;

45 Figures 5 illustrates a sectional view on the line 5—5 of Fig. 1; and

Figure 6 illustrates a view in elevation on the line 6—6 of Fig. 5.

In these drawings 10 denotes a stock 50 which may be of ordinary type, and 11 a nose on the end of the stock which may be held thereon by friction and by fastenings 12, such as screws or the like, the said nose having lips 13 and 14 oppositely disposed with relation to each other.

55 The edges of the lips are recessed or

serrated to form anchoring points which insure a firm hold of the nose or the lip of the nose when it is pressed into engagement with the log. The lip 13 is also 60 provided with recesses forming the engaging points 15 and it is to be used to hold the stock in proper position while turning logs or timber.

A clip or split band 16 is anchored on 65 the stock by a fastening 17 such as a screw, and the said clip has apertured ears or lugs 18 at its edges, the apertures of the said lugs being intended to receive the pivot 19 by which the shank 20 of the hook A 70 is oscillatably mounted with relation to the stock. The inner surfaces of the lugs are provided with shoulders 21 which are engaged by the hook to limit the oscillation of the hook in one direction, in order that it 75 may always be held distended and in position where the spur 22 may be in position to impinge the anchorage.

The spur 20 extends from the hook between the point of the hook end the angle 80 of the hook and shank, and the said angle forms a fulcrum which will cause the spur to be disengaged from its anchorage when the handle is properly manipulated. The hook and spur render it possible for an 85 operator to push or pull by simple manipulation of the handle in either direction, and, as stated, the spur can be readily disengaged by reason of the fulcrum afforded by the angular portion.

90 As shown, the spur is recessed as at 22 to form the two prongs 23 and 24, a condition which forms a firm anchorage and, to a great extent, prevents a tendency of the stock to oscillate laterally. The notch in 95 the spur also prevents the spur from seating too deeply in the timber and this prevents damage to the timber and allows it to be released without undue effort. On account of the width and angle of the spur, it will be prevented from slipping, and this is an added feature of advantage for this construction.

The spur is shown as in a direct line 100 with the pivot on which the hook is oscillatably mounted, and it will engage in any wooden surface without strain on the spur.

105 It will be observed that the cant hook A is pivoted to operate in a position opposite that occupied by the lips 13 and 14 in order that the lips may engage the

sides of a log or timber or any odd-shaped object that lies flat on a floor or ramp above, as the lips could be made to raise the object and lessen the friction when the hook is used as a fulcrum with the stock as a lever. This relation of parts prevents the end of the stock from slipping on the object to be moved. The edges of the lips are recessed or serrated, as has been stated, to form anchoring points which, when placed at an angle to the object to be moved, will insure a firm hold when the stock is used as a lever on the hook as a fulcrum. The log or object to be raised could be elevated and forced directed in a convenient direction away from the person using the device without the necessity of employing a hook on either end. If the nose were placed under an object to be moved, the spur will engage the side of the object to move it, as described

In a cant hook, a stock, a shank pivotally mounted on the stock, a hook on the outer end of the shank extending inwardly, a spur projecting from the face of the hook and extending outwardly approximately opposite to the direction of the hook, a nose-piece on the end of the stock below the pivot of the shank, anchoring elements projecting from opposite sides of the stock at an angle with relation to the axis of the stock, one of said anchoring elements being positioned to extend toward the hook and the other anchoring element being located on the opposite side of said stock and extending away from the said hook.

HALLIE D. SWAIN
